ARTHUR C. EASTWOOD, OF CLEVELAND, OHIO, ASSIGNOR TO THE ELECTRIC CONTROL-
LER AND MANUFACTURING COMPANY, OF CLEVELAND, OHIO, A CORPORATION OF
OHIO.

ELECTRIC SWITCH.

980,221.

Specification of Letters Patent.

Patented Jan. 3, 1911.

Application filed September 27, 1906. Serial No. 336,421.

To all whom it may concern:

Be it known that I, ARTHUR C. EASTWOOD, a citizen of the United States, residing at Cleveland, in the county of Cuyahoga and 5 State of Ohio, have invented or discovered new and useful Improvements in Electric Switches, of which the following is a specification.

My invention relates to improvements in 10 electric switches, said improvements being particularly applicable to switches of the so-called "power actuated type" as distinguished from the ordinary types of electric switches which are opened and closed by 15 hand.

The objects of my invention are to produce a power-actuated switch of great reliability in service, having a light and mechanically simple movable contact member; 20 having the contact members so arranged as to insure a clean contact of high carrying capacity; having the contacts so arranged with relation to the means for supporting the switch that the switch must necessarily 25 be so mounted that the interaction of the contacts may be readily inspected; having its parts so arranged that the contact members of the switch may be removed and replaced with maximum ease; and having a 30 blow-out magnet with its pole-pieces so arranged as not to interfere with the ready inspection and removal of the switch contacts, together with certain other features of construction which will later be described in 35 detail.

Power-actuated switches, as a general rule, are located at some distance from the operator and are not therefore under his direct observation. It is essential, therefore, 40 that the switches be reliable in action and that each switch should open promptly in response to the operation of the operator's switch or controller in deenergizing the actuating mechanism of the switch. To insure 45 this prompt opening of the switch I have devoted a great deal of attention to the arrangement of the contacts with a view to preventing welding or sticking of the co-operating contacts.

50 In all power-actuated switches as constructed in the past, so far as I know, the contacts of the switch have been very inaccessible for inspection and repair, it being impossible, or at least very difficult, to observe 55 the seating of the contacts one upon

the other. With my improved construction the contacts are so arranged that the interaction of the contacts can be readily observed. This feature is of importance in power-actuated switches, such, for instance, as are employed in the control of electrically-propelled trains. In such cases the failure of a switch to act properly may cause a serious wreck. With my improved construction, even when the switches are 60 mounted in the customary manner under the cars, the contacts will be accessible for inspection and are so arranged that they may be removed and replaced with minimum inconvenience and loss of time. 70

Referring now to the accompanying drawings, Figure 1 is a top plan view; Fig. 2, a front elevation, portions being broken away and the pole piece g^s being omitted; Fig. 3, a side elevation of one of my improved 75 switches; Fig. 4, a cross-section through the lever F and its adjuncts on a line through the screw f^s ; Fig. 5, a cross-section of the lever C and the wear-block c^s through the screw c^s ; and Fig. 6, a detail of a part of the 80 plate D and the pin g^s .

In the drawings I have in each case shown an electro-magnet for actuating the switch. It will be evident, however, that the electro-magnet might be replaced with an air-cylinder or other motive device without in 85 any way departing from the spirit of my invention.

In the figures, A is a slab of slate or other insulating material adapted to be supported 90 in a vertical position. B is the actuating electro-magnet having feet b^1 , b^1 , b^1 by means of which it is attached to the slab or base A. The electro-magnet B is provided with a magnetizing coil b^2 , wound upon a tube of 95 non-magnetic material b^3 . The upper end of the tube b^3 is closed by the plug b^4 of magnetic material. A plunger b^5 , of magnetic material, works vertically in the bore of the tube b^3 . The plunger b^5 is provided 100 with a tongue b^6 which extends through a slot in the plug b^4 and is attached by the pivot C to the movable contact arm C of the switch. When the electro-magnet is energized the plunger b^5 is attracted toward 105 the lower face of the plug b^4 , and rises vertically, thus actuating the switch arm to close the switch. When the electro-magnet is deenergized the plunger drops by gravity and opens the switch. The switch arm C is 110

pivoted on a pin c^1 , carried in bearings b^7 and b^8 at one end of the yoke b^9 of the electro-magnet. This yoke is also provided with the screws b^{10} , by means of which one of the 5 wires of the circuit controlled by the switch may be attached. A shunt or jumper C^2 of flexible copper ribbon is screwed at one end to the arm C and at the other end to the yoke b^9 . This shunt serves to carry current 10 around the pin c^1 and prevents heating of the bearings.

The yoke b^9 is provided with an upwardly extending bracket b^{12} to which is attached a block or plate of fiber or other good insulator, b^{13} , by means of bolts b^{14} . A metallic base-casting D is attached to the insulating plate b^{13} by bolts d^1 , d^1 , and is provided with two lugs d^2 and d^3 , the inner faces of which are finished to receive the contact brush E, 20 which is made of thin strips of copper or bronze riveted or sweated together to form a brush of the desired thickness. The brush is mounted in the pocket between the brackets d^2 and d^3 with its length at an angle to the switch arm C, this angle being preferably about 45° when the arm C assumes the horizontal or closed position. The end of the brush E is beveled so that the free end of each lamination makes contact with the upper 25 face of the arm C when the switch closes, and the other end of the brush E is similarly beveled so that when one end of the brush becomes worn the brush may be reversed end for end. This construction also permits of building up the brush of thin 30 strips, all of the same length. A set screw d^4 in the bracket d^2 , bearing upon a gib e^1 clamps the brush in place.

A metallic arm F is pivoted on a pin d^5 40 attached to the base D, and is cored out so as to clear the brush E. The outer free end of the arm F is provided with a "dove-tail" slot f^9 extending transversely across its under face and a carbon block f^1 is slipped into 45 this slot and held in place against transverse motion by a U-shaped piece f^2 which is slipped over the end of the arm so as to embrace the edges of the block f^1 and is held in place by a screw f^3 .

The movable switch arm C is provided at 50 its free end with a renewable L-shaped contact piece c^5 which is adapted to make contact with the under face of the carbon block f^1 when the switch closes, and is held in place by a screw c^6 .

The arm F is held on the pin d^5 by a washer d^6 and a cotter pin d^7 and is provided with an extension f^4 to which is attached one end of a tension spring f^5 . The 60 spring f^5 is insulated from the arm F by an insulating tube or spool f^8 which covers the pin f^4 on the extension f^4 . The other end of the spring is attached to a lug d^8 extending from the casting D. Motion, imparted to the arm F by the spring f^5 , is limited by the

stop f^8 on the extension f^4 which stop engages the lug d^3 , in which position the face of the carbon block f^1 extends considerably below the face of the brush E. When the switch closes through the energizing of the 70 electro-magnet B, the plunger raises the arm C. The contact piece c^5 first makes contact with the carbon block f^1 ; then the arm F is forced up against the action of the spring f^5 ; and the arm C comes into contact with the 75 brush E with a wiping motion due to the flexible character of the brush E and its angularity with the arm C.

When the electro-magnet B is deenergized, the plunger drops by gravity, the speed of 80 opening of the switch being assisted by the action of the spring f^5 also. In opening, the arm C first opens circuit with the brush E, the circuit being finally opened between the carbon block f^1 and the contact piece c^5 . All 85 of the arcing is, therefore, confined to these parts which may be cheaply and readily renewed. To cause the instant rupture of the arc which is formed when the circuit is opened at the contacts of the switch, I provide a blow-out magnet G. This magnet is 90 provided with a hollow core g^1 which slips over a stud g^2 attached to the base casting D. The magnetizing winding consists of a coil of 95 flat copper ribbon H, the inner end of which is riveted in the slot g^3 of the core g^1 . The outer end of the winding is provided with a terminal g^4 , to which one of the circuit wires, controlled by the switch, may be attached, by means of the screws g^5 . 100

The winding of the blow-out magnet is electrically connected to the core g^1 , which in turn is electrically connected to the base casting D by the stud g^2 . The magnet is provided with pole pieces g^5 and g^6 , the inner face of each pole piece being covered by an insulating plate g^7 . The pole pieces whose lower edges are indicated by the dotted line g^8 , are so located as to embrace between them the contacts of the switch so 110 that any arcing which takes place at the contacts is acted upon by the magnetic field. When the switch is closed current may enter at the terminal g^4 , pass through the successive layers of winding of the blow-out magnet G, (the successive layers being insulated from each other by layers of mica or asbestos) to the core g^1 , thence by the stud g^2 to the casting D and through the brush E 115 and the carbon block f^1 to the switch arm C, thence through the shunt C^2 to the yoke casting b^9 , current leaving the switch through the terminal b^{10} .

It will be understood that my improved switch is arranged to be mounted as shown in Fig. 3, this figure being a front elevation. Looking at this figure then, the parts of the switch are located as they would be in service. It will be seen that by simply removing the nut g^9 , the pole piece g^6 may be 120

slipped off. All of the contacts of the switch are then in full view and their action may readily be tested by raising the switch arm C. If it is desired or necessary the magnetizing coil may be removed from the stud g², it being simply drawn toward the observer. By loosening the set screw d⁴ the contact brush E may be removed edgewise toward the observer. By loosening the single screw 10 c⁶ which clamps it in place the renewable contact piece c⁵, at the end of the arm C, may be readily removed; likewise, by removing one screw f³, the carbon block f¹ may be slipped out in a direction toward the observer. By removing the cotter pin d⁷ which 15 holds it in place on the stud d⁵ and by unhooking the spring f⁵, the entire arm F may be removed. It must be evident also that the movable switch arm may be made light in 20 weight and is of simple construction.

I do not restrict my invention to the details shown and described as they and their combination may be variously modified without departing from the spirit thereof.

25 I claim—

1. In an electric switch, the combination of one switch member comprising a conducting base, a stiff metallic arm, pivoted on said base and carrying near its free extremity a 30 renewable arcing tip, there being an aperture in said switch arm between its pivot and its free end, a contact brush, clamped to said conducting base and having its end projecting through the said aperture, and a second contact member comprising a swinging main contact arm, having at its free extremity a renewable arcing tip adapted to co-operate with the arcing tip at the extremity of the first mentioned pivoted arm and having 35 between said arcing tip and its axis a contact face adapted to coöperate with the end face of said contact brush.

2. In an electric switch, a relatively stationary contact brush having a contact face, 40 a pivoted switch arm electrically connected to said brush and having its axis on one side of said brush and an arcing contact on the other side of said brush, and a pivoted main switch arm having an arcing contact 45 coöoperating with the arcing contact on said first mentioned arm and a contact face intermediate its free end and its axis adapted to coöperate with the contact face of said brush.

3. In combination, a frame, an electro-magnetic winding carried thereby, a plunger adapted to be actuated by said winding, a pivoted contact arm pivotally connected to said frame, a contact support mounted upon said frame, a yielding contact carried by 55 said support and arranged to engage said contact arm at a point intermediate of its ends, a contact holder pivotally mounted upon said support, a carbon contact carried by said support and arranged to engage the 60 free end of said arm, and a spring exerting a yielding force upon said contact holder when said carbon contact is engaged by said arm.

4. In an electric switch, the combination 70 with a supporting frame, of a switch member pivoted thereto, a solenoid mounted in said frame and having a plunger connected to said switch member, and a stationary laminated contact mounted on said frame and 75 arranged to engage said switch member at a point contiguous to its connection with the plunger of said solenoid, said contact being obliquely disposed to said switch member.

5. In combination, a magnet frame, an 80 electro-magnetic winding carried thereby, a plunger adapted to be operated by said winding, a contact member pivoted upon said frame and mechanically connected to said plunger, a contact support mounted 85 upon said frame, a laminated brush carried thereby and inclined from its point of attachment to the point of connection between said plunger and said member.

6. In combination, a magnet frame, an 90 electro-magnetic winding carried thereby, a plunger adapted to be operated by said winding, a contact member pivoted upon said frame and mechanically connected to said plunger, an insulating base mounted 95 upon the frame, a contact support carried thereby, and a laminated brush carried by said support and inclined from its point of attachment toward a point contiguous to the point of connection between said member 100 and said plunger.

Signed at Cleveland, Ohio, this 24th day of September, 1906.

ARTHUR C. EASTWOOD.
